UNITED STATES PATENT OFFICE.

FREDERICK T. MOORE, OF GEYSERVILLE, CALIFORNIA.

BRIDLE-BLIND.

No. 923,289.

Specification of Letters Patent.

Patented June 1, 1909.

Application filed July 16, 1908. Serial No. 443,822.

To all whom it may concern:

Be it known that I, FREDERICK T. MOORE, a citizen of the United States, residing at Geyserville, in the county of Sonoma and State of California, have invented certain new and useful Improvements in Bridle-Blinds, of which the following is a specification.

My invention relates to blinds for bridles, 10 and has for its object to provide certain improvements over the construction disclosed in Letters Patent No. 887,338, granted to me May 12th, 1908, as will be hereinafter more particularly described and claimed, 15 reference being had to the accompanying drawing, in which:

Figure 1 is a perspective view of my improved construction shown attached to a bridle in position on a horse's head. Fig. 2 20 is an enlarged detail plan view of the blinds, one of the same being shown in section. Fig. 3 is an enlarged detail perspective view of one of the springs. Fig. 4 is a view similar to Fig. 2, illustrating a modified construction.

In the said drawing, referring to Figs. 1 and 2, the reference numeral 1 denotes the usual side strap of the bridle, and 2 the throat latch thereof. Fixed to said side strap in the 30 usual manner are my improved blinds 3, the same being preferably formed of a plurality of layers of leather, and preferably having located between the outer and inner layers thereof the springs having their ends 35 4 extending for a distance in opposite directions between said layers, and their central coiled portions 5 projecting through apertures in the inner layers of said blinds, all as described in my Letters Patent hereinbefore referred to, whereby said blinds will be normally maintained in their open position. 40 Connecting the outer ends of said blinds at their upper and lower ends are two springs having their body portions 6 lying normally 45 parallel and coiled at their centers at 7 to maintain this position, the ends 8 of said springs being bent to lie within the layers of the blinds at their outer vertical ends. Attached to the upper and lower outer ends of 50 said blinds are the straps 9 and 10, that are crossed across the face of the horse, and passed through eyelets 11 fixed to the side straps 1, said straps being connected at 12

to a common strap 13, that in turn is attached to a rein 14 leading back to within 55 reach of the driver.

In use the spring ends 4 and the body portions 6 will normally maintain the blinds in the position shown in full lines in Fig. 2, but when the rein 14 is pulled, the straps 9, 10 60 and 13 will be drawn backward, thereby folding the outer ends of the blinds toward each other, as shown in dotted lines in Fig. 2, and causing the same to completely cover the eyes of the animal, the body portions 6 65 of the springs bowing outward, as shown in dotted lines in Fig. 2.

While I prefer to employ the spring arms 4 in the blinds 1, the same may be dispensed with, as the other springs alone will serve to 70 normally maintain the blinds in their open position.

In Fig. 4 I have illustrated a modified construction wherein are employed upper and lower rigid cross-bars 15, connecting the 75 blinds 1 at their bending points, said bars being coiled at each end at 16 and having their outer ends 17 lying horizontally within the layers of the blinds and extending outwardly therein. With this construction 80 when the rein 14 is pulled the outer ends of the blinds 1 are folded against the tension of coils 16, while the body portions of said blinds are firmly maintained in their normal position by the cross-bars 15, thereby preventing side pressure on the eyes of the animal. 85 In this construction the horizontal spring ends 4 may or may not be employed, as desired.

Having thus described my invention, and 90 in what manner the same is to be performed, what I claim as new is:

1. The combination with a bridle, and a pair of blinds connected thereto, of spring arms connecting said blinds and supported 95 solely thereby and adapted to maintain said blinds in a flat position but adapted to yield under a pull to permit said blinds to fold.

2. The combination with a bridle, and a pair of blinds connected thereto, of spring 100 arms connecting said blinds at their outer ends and supported solely thereby, adapted to normally maintain said blinds in their open position, and adapted to bow centrally under a pull on said blinds to permit the 105 latter to fold.

3. The combination with a bridle and a pair of flexible blinds connected thereto, of a spring arm embodying body portions normally maintained in substantial parallel relation through an intermediate spring portion, and bent ends engaging the outer ends of said blinds to normally maintain the latter in their open position, said spring arm adapted to bow at its intermediate spring portion

under a pull on said blinds to permit the latter to fold.

In testimony whereof I affix my signature, in presence of two witnesses.

FREDERICK T. MOORE.
